Primary Examiner — Darlington Ly(74) *Attorney, Agent, or Firm* — Westman, Champlin & Koehler, P.A.(57) **CLAIM**

The ornamental design for a front fork as shown and described.

DESCRIPTION

FIG. 1 is a top perspective view of a second embodiment of a front fork showing my new design;

FIG. 2 is a front perspective view thereof;

FIG. 3 is a back perspective view thereof;

FIG. 4 is a right side view thereof;

FIG. 5 is a left side view thereof;

FIG. 6 is another top perspective view thereof; and,

FIG. 7 is a bottom perspective view thereof.

The broken lines in the drawings are included for purposes of illustrating portions of the front fork and form no part of the claimed design.

1 Claim, 5 Drawing Sheets(56)
